UNITED STATES PATENT OFFICE.

WILLIAM M. CONWAY, OF BALTIMORE, MARYLAND.

MEANS FOR CONDUCTING ELECTRIC WIRES.

SPECIFICATION forming part of Letters Patent No. 243,853, dated July 5, 1881.

Application filed May 9, 1881. (No model.)

To all whom it may concern:

Be it known that I, WILLIAM M. CONWAY, a citizen of the United States, residing at Baltimore, in the State of Maryland, have invented 5 certain new and useful Improvements in Means for Conducting Electric Wires; and I do hereby declare the following to be a full, clear, and exact description of the invention, such as will enable others skilled in the art to which it applies to make and use the same, reference being had to the accompanying drawings, and 10 to the letters or figures of reference marked thereon, which form a part of this specification.

15 This invention relates to means for conducting telegraph, telephone, and other electric wires underground in a manner which shall admit of placing a large number of wires within a small area and allow the ready removal of 20 any separate wire for purposes of examination and repair.

In carrying out my invention I employ a system of boxes, constructed of iron or other metal, or of glass, terra-cotta, or other material, which boxes are laid or arranged at the outer edge or curb of the sidewalk, or in the middle of the street, or in any other convenient location. The cap-plates forming the closed tops of the boxes are placed on a level with 25 the pavement or street, and constructed in such a manner and of such strength as to adapt them to the traffic or usage to which they may be subjected. Each end of each box is arranged to unite or interlock with an end of 30 the adjacent box in a manner constituting a water-tight joint. Arranged within each box are one or more partitions, formed of glass, india-rubber, or other insulating medium, which are provided with one or more slots, leading 35 from the top edge down to near the bottom, and having branch slots, which latter are at their ends formed into curved recesses to receive and support the various wires. The cap-plate of each box is laid upon the upper edges 40 of the box sides, and secured thereto in any appropriate manner which will effect a water-tight joint.

A modification of the invention consists in the employment of wires in sections instead of 45 continuous wires. In the use of the sectional wires certain changes in the sustaining parti-

tions are necessary, as will hereinafter more fully appear.

In the further description of my invention which follows, Figure I is a longitudinal section of the invention. Fig. II is a plan view with the cap-plate removed. Fig. III is a transverse section. Fig. IV is a transverse section, showing a modification of the invention. Fig. V is an under-side view of the cap-plate. Fig. VI shows a modification of the invention in the use of sectional wires.

Similar letters of reference indicate similar parts.

A A represent the box-sections, which may be constructed of metal, glass, earthenware, or other material. The sides and bottom at each end of each box-section are formed with devices for effecting a water-tight joint between it and the adjacent section. As shown by a 65 and b, the mode of effecting the joint here employed is by a tongue and groove, although I do not restrict myself to this particular arrangement.

B indicates the partition-plate, of which one 70 or more may be used with each box-section, the number being determined by the length of the section or other consideration. The partition is loosely inserted in the box, resting in a groove, c, formed by lugs cast or secured on 75 the inner side of the box, as shown. The partition B is provided with one or more slots or leaders, d, each commencing or starting from the upper edge of the partition, and descending preferably in a perpendicular line to near 80 its lower part, the slot or leader being of sufficient width to receive the wire. Branching in any desired directions from the main slot or leader are similar slots d', terminating each in a circular recess, d'', which recesses form the 85 beds or supports for the wires, as shown particularly in Figs. III and IV. As exhibited in Fig. IV, two leaders with branch slots are used in the partition. As represented in Fig. III, only one is shown; but it is intended to be indicated by this figure that any suitable number may be employed.

C is the cap-plate, which may be formed of metal, earthenware, or glass, and, as shown, is provided with a roughened upper surface, in order that it may form a part of the pavement or road. I prefer that the cap-plates, which

may be fastened to the box in a suitable way, shall break joints with the box-sections, as shown particularly in Fig. I at *e*, the uniting ends of the cap-plates resting upon the cross 5 bar or strip *f*; but this arrangement and mode of supporting the cap-plate, not being essential to my invention, may be departed from. The underside of the cap-plate is grooved, as shown in Fig. V, and the top edges of the box tongued, 10 as shown more particularly in Figs. III and IV, in order that with the aid of rubber, if necessary, a tight joint may be effected between the cap-plate and box.

As represented in Fig. VI, I employ, instead 15 of the continuous wires shown in Figs. I and II, wires formed in sections of, say, five feet in length, provided at each end with a metal button, *g*. In this construction it is necessary to employ a pair of partitions placed a short 20 distance apart, in order that the buttons of two connecting wires may be received between the partitions, so as to connect the wires, and thus properly conduct the electric current. This modification of my invention admits of the 25 convenient removal of the wires for repairs or other purposes, and avoids the necessity of uniting the wires by coiling or twisting, as is the ordinary practice.

My invention, whether used with the continuous or sectional wires, admits of the following advantages: It is seen that a large 30 number of wires can be inserted in a very small area, and that any of the wires can be safely lifted or removed without interfering 35 with the rest of the series. Further, the partitions being removable, the entire series or nest of wires can be lifted out for examination the slack where the continuous wire is used admitting of the act. The removal is, however, 40 facilitated where the wires are used in sections. The sectional construction of the boxes, with the mode of uniting the several sections with water-tight joints, in the manner described, has many obvious advantages, as 45 has also the mode of effecting the water-tight joint between the cap-plate and the box.

I do not restrict myself to the mode of locating the box, or to the mode of effecting the water-tight joint between the sections or between the box and cap-plate. It is, however, 50 necessary to my invention that the partitions be provided with leaders whose open ends shall be exposed on the removal of the lid, and that such leaders shall be provided with 55 branch slots serving as rests for the wires.

The advantage of my arrangement of leaders and branch slots is that it admits of the distribution of the wires to any point of the area of the partition, as it is seen that any point may be readily reached by carrying 60 thereto a branch slot. Furthermore, the separate rests for the wires are so distinctly isolated that there is no possibility of one wire becoming detached from its rest and caught in the rest designed for another wire. Further, 65 in the act of removing the wires there is no possibility of accidental displacement of a wire not designed to be moved.

I disclaim partitions which are provided with simple notches for the reception of the wires, 70 as also hooks and other similar devices serving as rests for the wires; but,

Having described my invention, I claim—

1. A series of sectional boxes each provided with a removable partition or partitions 75 having entrance slots or leaders and branch slots serving as rests for the wires, the open ends of the leaders extending to the top of the box, and the branch slots being carried from said leaders to different points of the area of 80 the partitions, serving to appropriately distribute the wires throughout said area, substantially as set forth.

2. A series of underground boxes for electrical wires, said boxes being formed with water-tight joints, combined with cap-plates and removable partitions having entrance slots or leaders whose open ends extend to the top of the box, said leaders being provided with branch slots reaching to different points within 85 the area of the partition, and serving to 90 distribute and act as rests for the wires at different points in said area, substantially as specified.

3. In combination with a series of box-sections provided with slotted partitions arranged in pairs, a series of sectional wires whose ends are provided with engaging buttons adapted to rest between the partitions, and thus unite the wires and complete the circuit, substantially as specified. 95

In testimony whereof I affix my signature in presence of two witnesses.

WILLIAM M. CONWAY.
